UNITED STATES PATENT OFFICE

JOHN R. WARREN, OF GRAND RAPIDS, MICHIGAN, ASSIGNOR TO CATHERINE McGOUGH AND FRANK RAYMOND McGOUGH, DOING BUSINESS AS E. H. McGOUGH & SON, OF GRAND RAPIDS, MICHIGAN

KNIFE

Application filed December 20, 1930. Serial No. 503,706.

The present invention relates to knives and more particularly to knives especially adapted for use in cleaning vigil candle glasses.

The main objects of the invention are to 5 provide a knife particularly adapted for cleaning the glasses of vigil candles or votive lights; to provide a device of the character indicated above by which vigil candle glasses may be readily, conveniently and quickly 10 cleaned; to provide a knife whereby the old candle wax and the metal wick disc may be removed in one operation; and to provide a knife or scraper which is economical to manufacture, and convenient and practical in use. 15 An illustrative embodiment of the invention is shown in the accompanying drawing wherein:

Figure 1 is a front elevational view of the device;

20 Figure 2 is a perspective view of a vigil candle or votive light;

Figure 3 is a cross sectional view taken on line 3—3 of Figure 1;

25 Figure 4 is a cross sectional view taken on line 4—4 of Figure 1;

Figure 5 is an end elevational view of the blade portion of the knife; and

30 Figure 6 is a fragmentary sectional view showing the improved knife or scraper with in the vigil candle glass as used during the cleaning operation thereof.

The device herein shown and described is as above indicated, particularly designed and intended for cleaning church vigil candle or 35 votive light glasses although the device may likewise be used for cleaning censer pots, thuribles and the like.

Referring to the drawing the knife is preferably of stamped sheet metal and is provided with a handle 1 of conventional form and an elongated blade 2 of concavo-convex form. 40

The elongated sides of the blade are provided with cutting edges 3, 4 and a transversely disposed cutting edge 5 is provided adjacent 45 its bottom end.

Vigil wax candles 6 such as are used in 50 churches are placed within the candle glasses 7 and the wick 8 of the candle is conventionally secured by a metal disc 9. A pick 10 on the cutting edge 3 near its lower end is

formed by blanking out a semi-circular portion of the blade during the stamping operation and the metal disc 9 can thus be conveniently removed by the pick during the cleaning operation. 55

It will thus be seen that the old candle wax and the metal wick disc may be readily removed in one operation and that the knife herein shown and described is economical to manufacture and convenient and practical in use. 60

While but one specific embodiment of the invention has been herein shown and described, it will be understood that numerous details of the construction shown, may be altered or omitted without departing from the spirit of this invention as defined by the following claims: 65

I claim:

1. In a device of the class described, an elongated blade of concavo-convex form provided with cutting edges adjacent both its longitudinal sides, and a pick on one side of said cutting edges near its lower end. 70

2. In a device of the class described, an elongated blade of concavo-convex form provided with cutting edges adjacent both its longitudinal sides, a cutting edge adjacent its bottom end, and a pick on one side of said cutting edges near its lower end. 75 80

In testimony whereof I have hereunto set my hand at Grand Rapids, Michigan, this 11th day of December, 1930.

JOHN R. WARREN.
